United States Patent Office

Des. 210,745
Patented Apr. 9, 1968

210,745

DISHWASHER

Raymond C. Sandin, Winnetka, Ill., assignor to General Electric Company, a corporation of New York

Original design application June 30, 1966, Ser. No. 2,888,
now Patent No. 208,942, dated Oct. 17, 1967. Divided
and this application Feb. 3, 1967, Ser. No. 7,046

Term of patent 14 years

(Cl. D49—1)

FIG. 1

FIG. 2

FIG. 3

FIGURE 1 is a front elevational view of a dishwasher, showing my new design;

FIGURE 2 is a fragmentary cross-sectional view thereof, taken along the line 2--2 of FIGURE 1; and

FIGURE 3 is a side elevational view thereof.

The side not shown has substantially the same appearance as the side shown.

The dominant features of my design reside in the portions shown in full lines.

It is to be understood that the broken line showing of the surface ornamentation partially applied to the panel of the dishwasher shown in FIGURE 1 covers the entire area encompassed thereby.

This application is a division of my copending design application Ser. No. D. 2,888, filed June 30, 1966, now Patent No. D. 208,942, granted Oct. 17, 1967, and assigned to the General Electric Company, assignee of the present invention.

I claim:

The ornamental design for a dishwasher, substantially as shown and described.
